UNITED STATES PATENT OFFICE

WILLIAM C. HUEBNER, OF BUFFALO, NEW YORK

PROCESS OF PREPARING AND REGISTERING PRINTING SHEETS OR FILMS

Application filed July 31, 1924, Serial No. 729,277. Renewed May 5, 1928.

This invention relates to a process whereby image-bearing sheets or films for use in multicolor printing and the like, or for other purposes, may be prepared or treated so as to control the register of the images thereon and of the prints made therefrom.

It has been customary to use glass plates for the production of a series of multicolor photographic negatives or positives from an original of any sort, or for the production of negatives or positives of other kinds adapted to be used, for instance in the preparation of metal or other press printing plates.

In the production of the printing plates, for instance for poster work, the use of glass plates or lithographic stones is very expensive, and further, owing to the large area to be covered, the job must be done in sections, that is, a number of separate plates are used, each bearing a different portion of the final picture or image, and these portions must not only register accurately with the original image, or with a layout sheet or the like, but the abutting edges of the sections must register accurately with each other.

As is well known, there are many disadvantages in the use of glass for this purpose. The surfaces of the glass plates are sometimes not flat but wavy, and at other times the opposite faces of the plates are not parallel; again there are variations in the thickness of a series of glass plates for one color job, or for the different sections of a large image. These imperfections in the glass add to the difficulties in registration of the images on the press plates, and also prevent perfect contact between the glass plates and the press plates or print-receiving surfaces. Further, it is difficult to handle large plates of glass in quantity production during the various operations of exposure and development and the other finishing operations; many plates are broken in various ways, such as by cracking, due to uneven pressure as a result of the uneven surfaces or varying thickness before mentioned. Finally, the expense attendant upon the use of glass plates is very great, as large quantities of glass are accumulated, resulting in a large unproductive investment, and expense and inconvenience in the stor-

age of the glass which requires considerable space and appliances for the handling and the protection of the stock.

The desirability of using flexible films or sheets bearing photographic or other printing images, in place of the glass plates has long been recognized, the advantages to be obtained including cheapness and variety of the material as compared with glass, ease of handling and storing, and freedom from breakage. Also perfect contact between the flexible image bearing films or sheets and the print-receiving surface can readily be obtained. Moreover, the relatively uniform thickness of photographic films, paper, tracing cloth and other materials adapted to bear printing images makes the use of such materials very desirable for multicolor work.

However, the use of such films or sheets for multicolor or other work requiring a number of images that must all register exactly as to dimensions and position one with another and with the original or with a master copy, layout or other registering device or guide, has not heretofore been considered feasible owing to the characteristic tendency of the materials of which the films or sheets were made to shrink and expand or otherwise change condition either generally or locally, which would cause misregister of the prints made from the sheets, hence nullifying the otherwise desirable qualities of such films or sheets. The films or sheets not only change form or dimensions, due to their immersion in water and other liquids and their drying during the development, washing, etc., of the sheet, but they are affected by subsequent humidity and temperature changes in the atmosphere which cause changes in the condition and dimensions of the sheets from time to time.

One of the objects of the present invention is to provide a process whereby flexible films or sheets of material bearing photographic and other printing images may be employed and the advantages thereof realized in the production of printing plates or elements bearing images of a subject or subjects, so that nevertheless all of the images of the sub-

55

60

65

70

75

80

85

90

95

100

ject or subjects may be registered exactly one with another in accordance with the requirements of the work.

- Another object is to utilize the natural characteristics of the material forming the film or sheet, of changing dimensions with variations in humidity and temperature, in the preparation or manipulation of the films or sheets in such a way that one or more prints of a given subject may be brought to required predetermined dimensions, or that the images thereon may all be brought to exact register with a master image or other registering guide, and also that a plurality of sectional images, each on a separate sheet, may be produced and be adapted to register or match with the adjacent sections to form a continuous, unbroken whole.

Another object is to prepare the films or sheets after registration, so that they are adapted for use as printing elements in a photo composing or other photographic printing apparatus for making metal or other press plates, and so that they will retain their images in registered size and exact predetermined position during such use, regardless of ordinary atmospheric changes; also to so prepare the films or sheets that they will be substantially unaltered by subsequent atmospheric changes or moisture, and will only need a simple manipulation to register them again with the original master image, guide or layout, or with one another, or to bring them to the predetermined size to which they were originally made.

In the accompanying drawings:

Fig. 1 is a plan view of a flexible sheet or film arranged on a frame on which it may be treated in accordance with this invention.

Figs. 2 and 3 are transverse sectional views showing the released and holding positions respectively of one of the gripping devices or clips for securing the flexible sheet on the frame shown in Fig. 1.

Fig. 4 is a transverse sectional elevation of the frame and sheet arranged in relation to a light opening in a light box or chamber.

Fig. 5 is a plan view showing the use of an image positioning device or guide for determining the position of an image on the flexible sheet or film.

In preparing a film or sheet, such as one of a plurality of color negatives of a subject in accordance with this invention, the sheet on which an image has been made by photographic or other method is mounted on a suitable frame, preferably portable, having a light aperture or opening over which the sheet extends and equipped with clips or holding devices which are suitably formed to grip or hold the edges of the sheet, and are adapted to be adjusted relatively to the frame to draw the sheet smooth and taut thereon, and also to stretch or extend the sheet. The frame preferably includes a bearing ridge or por-

tion extending all around the aperture on which the marginal portions of the sheet are adapted to bear, and the clips are arranged outwardly beyond said bearing ridge so that they may be manipulated to draw the sheet perfectly flat and smooth across the opening in the frame. Said bearing ridge or portion is also disposed with reference to the holding clips and other parts of the frame so that the sheet is held in a plane outwardly beyond or at least flush with the outermost parts on the frame, which therefore, cannot prevent uniform and perfect contact between its face of the sheet and a flat printing plate or surface which may project beyond one or more edges of the sheet. The sheet is now moistened in any suitable way, or is otherwise suitably treated to render it extensible, and the clips or holding devices are then manipulated to stretch the sheet either generally or locally, as required, until the image or register marks thereon register approximately with a master image or other registering device or guide in juxtaposition therewith, or until by measurement or other method the image or register is ascertained to accord in size and position with the required predetermined layout or registering and checking means. In some cases more than one moistening and stretching operation will be necessary to bring the image or register marks on the sheet approximately to the required positions, in which event the sheet is dried between successive stretching operations.

After the approximate register has been obtained, by moistening and stretching as stated, the sheet is dried thoroughly while being maintained in the stretched condition, and is then treated to make it impervious to moisture and prevent variations therein due to atmospheric changes, as by applying a suitable oil, varnish, or lacquer to the sheet. When this has been done the sheet is given a final tightening or stretching to bring it to exact register by either of the above methods of registration, after which the sheet may be used, still on the frame, in a photographic printing machine or otherwise, to obtain one or more images or prints therefrom on a print-receiving surface, such as a metal press plate; or a number of sheets prepared as described and bearing different color images of a subject may be so used to produce a set of accurately registered color printing plates.

In the drawings, Fig. 1, a sheet or film A is shown, bearing images 10 and register marks 11, which are to be registered with like images and register marks 10^a and 11^a respectively, on a registering plate B. The images 10 and register marks 11 are shown as being out of register with the images 10^a and cross marks 11^a due to the shrinking of the sheet after the production of the images thereon. It is, therefore, necessary

to treat the sheet as explained so that it may be stretched to bring the two sets of images and register marks into exact register.

5 A frame and holding and stretching devices of any suitable sort may be used for the purpose stated, but preferably a frame and devices of the construction shown in the drawings are employed. While this 10 construction is specially adapted for use in carrying out the process of the present invention, it is not specifically claimed herein, as the same forms the subject matter of a separate application for Letters Patent, 15 Serial Number 742,919, filed Oct. 10, 1924.

Briefly described, the frame, designated C, and the holding devices or clips D, are constructed and arranged as follows:

The frame C comprises side and end bars 20 or members 12 adjacent the inner edges of which, surrounding the light aperture or opening 13 of the frame, is arranged a continuous ridge or bearing portion 14. This bearing ridge is preferably formed by a 25 strip of rubber or analogous resilient or yielding material seated in a channel strip 15 secured on and extending outwardly from the face of the frame so as to support the sheet or film A off the face of the frame 30 and spanning over the opening 13. A plurality of the clips or film gripping devices D is adjustably positioned on the frame B outside of the ridge 14 so that they may be moved both endwise and sidewise relatively 35 to the ridge 14. Each of the clips D comprises a pair of gripping members 18, 19 one of which, 18, is adapted to bear and slide on the frame bars 12. The other member 19 overlies the member 18, one end of 40 the member 19 having a jaw 20 adapted to be moved to and from a jaw 21 on the member 18 while its other end fulcrums on a rib 22 on the member 18, remote from the jaws 20 and 21. The jaws 20 and 21 are 45 normally held in open position by suitable means, such as a leaf spring 23 between the clip members so that the edge of the sheet or film A may be readily inserted in or removed from the clip. Each clip is provided with one or more pivoted eccentrics or cam levers 24, adapted to be swung or depressed to act in opposition to the springs 23 and force the clip member 19 towards the other member 18, so that the jaws 20, 50 21 will firmly grip the edge of the sheet A. The clip members 18 are provided with opposite, laterally projecting lugs 25 loosely extending beneath retaining plates or parts 26 secured or formed on the frame, so that 55 the clips can be moved on the frame endwise and laterally and can also assume slightly oblique positions while being prevented from disengagement therefrom. When the edges of the sheet have been secured in the 60 jaws of the clips, the latter can be adjusted

to tighten or stretch the sheet as required by suitable straining or clip actuating devices for each clip, such as a screw 27 having a head 28 engaging the outer face of a fixed flange or rib 29 extending upwardly from the frame bars 12, parallel to and spaced from the bearing ridge 14, outwardly beyond the clips D. The threaded shank of the screw 27 extends loosely through an elongated aperture or slot 30 in the rib 29 and is received in a threaded hole in a lug 31 of the member 18 of the clip D. By turning the screw, the clip may be moved to and from the ridge 14 and it may also be moved laterally and obliquely within the 70 limits of the slot 30. It will be observed that the clips D, flange 29 and screws 27 are all located between the plane of the outer face of the ridge 14 and the upper face of the bars 12, with the jaws 20, 21 relatively near this plane, so that when the edges of the sheet are secured in the jaws, the sheet may be drawn taut over and down on the bearing ridge 14, and none of the parts on the frame will project beyond the outer 80 face of the sheet or film so as to interfere with the close contact of the sheet or film with an opposing flat surface even if the latter should project beyond the edge or 85 edges of the sheet.

The registering plate B, bearing the image or register marks with which it is desired to register the image or marks on the sheet, may be secured relatively to the frame C in any suitable manner, for instance, as shown 90 in the drawings, the plate is removably secured directly in the frame opening by wedges, quoins or the like 33 with its image bearing surface close to and preferably in contact with the under side of the sheet A.

The frame C with the sheet A and registering plate B may be conveniently placed relatively to a suitable source of light, as by placing it over the opening 34 of a suitable light box or chamber E, see Fig. 4, so that light may pass through the plate B and sheet A which are transparent or translucent, to illuminate the images thereon and permit them to be clearly seen. The frame may be stationarily arranged and secured on the light box in a predetermined position thereon by any suitable means, such as by dowels 35 on the top of the light box which enter dowel holes 36 in the under side of the frame. When the sheet A has been secured on the frame C and the clips D have been adjusted sufficiently to draw the sheet taut over the opening 13, the relative positions of the images on the sheet and plate are noted, and if it is found that the sheet is shrunken so that its images 10 or register marks 11 are out of register with the images 10^a or register marks 11^a of the plate B, as indicated for instance in Fig. 1, the sheet is treated in accordance 100 with the process of this invention to render 105

it extensible either as a whole or in part only, and is stretched or manipulated to bring the images 10 and register marks 11 first into approximate registration, and then into final accurate registration with the images 10^a and register marks 11^a.

The preferred treatment for the sheet is to render it extensible, as by the use of water, applied either as a spray or in the form of steam or vapor, or by direct application of water with a sponge or the like. In some cases a solution of water and other substances may be used, or a greasy solution may be called for, depending on the composition of the sheet or film and the degree of saturation required.

The application of moisture will soften the sheet somewhat and enable it to be stretched to a certain extent without injury, and while in this condition the screws 28 are manipulated to pull the marginal portions of the sheet over the ridge 14 and thereby stretch the desired portions of the sheet, or the whole sheet to shift and draw its images and register marks into register with those on the registering plate B. There is, of course, a limit to which the sheet may be safely stretched after the soaking or moistening step, and if, after it has been stretched, in the judgment of the operator, to such a limit, and the images are not in approximate register, the sheet is dried as by the application of heat from a suitable heater, or by the use of a fan, or both, while the sheet is under tension, and then the sheet is given a further moistening and stretching, and again dried as before. In this way the sheet may be gradually and safely stretched until the required registration is obtained. In some cases it may only be necessary to moisten and dry the sheet once to obtain the desired result. In either case, after approximate register has been obtained, and the sheet has been thoroughly dried, it is given a final treatment such that it may be once again slightly stretched into final accurate registration, which treatment consists in treating or coating the sheet while still under tension on the frame C with a suitable medium, such as oil, varnish or lacquer, for rendering it slightly limp and at the same time impervious to further moisture.

In cases where the sheet is formed of paper, tracing cloth or the like, the use of the oil in addition to making it capable of being stretched slightly, gives the sheet the necessary transparency required to adapt it for use as a transparent photographic negative or printing element. After the oil has been applied to the sheet, the clips are again adjusted and the sheet stretched until its images or register marks are in accurate register with the images or registering parts of the registering plate or device.

In some cases the flexible film or sheet

bears an image made to a different scale, or is larger or smaller than the original from which it was taken, but which has been nevertheless made to a required predetermined measurement and is provided with register marks to facilitate the registering of the image. However, owing to the fact that this sheet is susceptible to expansion and contraction more or less in the treatments to form the image, and also may vary in dimensions after such treatments, due to atmospheric changes, the image will not be the exact size it was made, and its register marks will not correspond to the predetermined requirements. Obviously, the scale of the image being different from the image on the original plate, stone or other element, the image on the sheet cannot be registered therewith by visual observation, as in the case of the sheet A and plate B.

When, therefore, such an image is to be registered, different registering means are employed. For instance, after the sheet has been mounted in the frame C with its edges secured in the clips D as before, the frame with the sheet thereon can be placed into operative relation to a source of light as before, and also to a suitable image registering and checking apparatus, the apparatus shown in Fig. 5 being well adapted for this purpose. This apparatus if provided with graduated scale bars F F' disposed at right angles to each other and adapted to be adjusted relatively to each other and to the frame C over the face of the sheet, so that, when the sheet is moistened or oiled as before described, the sheet may be stretched and the register marks thereon accurately checked or registered as required with reference to the scale bars. The frame C may be conveniently arranged and held in a predetermined, operative position relatively to the registering and checking apparatus, as by means of dowels or the like 40 on a support G, preferably in the form of a lamp box, said dowels being adapted to enter the complementary recesses 36 before mentioned in the frame C. The scale bar F spans the frame C and the light opening in the support G and is adapted to be secured in one or another predetermined fixed position relative to the frame C, as for instance by dowels or the like 41 at the ends of the bar F, adapted to enter holes 42 in the support G at opposite sides of the frame. The other scale bar F' is slidably mounted on the first scale bar F so that it is always retained at right angles thereto but can be adjusted and secured at different points lengthwise of the bar F by a securing device 43 of any suitable kind. The scale bars can then be placed so that suitable register marks on the sheet can be registered accurately with the edges of the bars and their positions noted by reference to the scales so that the same sheet can be repeatedly placed in the same position,

or different sheets placed in exactly like positions on the frame C. This construction and arrangement is shown as being illustrative of means for registering and checking the images or register marks on the sheet, but any other suitable apparatus or devices may be employed.

The described process is simple and practical, and one of the great advantages there-
10 of is due to the fact that a plurality of images or layouts may be made at any convenient time on inexpensive flexible films or sheets of paper or other material adapted to the purpose, and stored without regard to the

15 effect of changing atmospheric conditions on the size of the image, as the process enables the sheets to be treated as described immediately before they are required for use, and after oiling, varnishing or the like, the frame
20 with the sheet in place therein can be placed in a photographic printing apparatus to produce one or more printing plates therefrom, either by contact or projection methods. After use, the sheet may be stored in any suitable way, and when again required, it is only necessary to place it on the frame and adjust it to the initial checking or registering, as after being oiled, the sheet changes very little, if any, in size.

25 30 While in the foregoing description, the process has been explained in connection with the registration only of one sheet or film, it is intended that the invention be understood as being particularly applicable to the registration of a plurality of sheets, such as a set of color images from a single original subject, all of which images must register accurately with each other as well as with the original image or with the predetermined 35 measurements thereof. This may be done, either by registering each sheet separately directly with a master image as before described, when the same size, or by successively registering the sheets by means of any suitable registering and checking device or guide 40 when they are to be made to a different scale than the original.

In each case, a set of images or the like 45 may all be brought to uniform register one with another regardless of different or varying degrees of initial misregister of the images on the sheets.

I claim as my invention:

50 55 1. The hereindescribed process of treating a flexible film or sheet bearing an image to cause said image to register with a registering guide, which consists in treating said sheet to render it extensible, then stretching said sheet as necessary while in such extensi-
60 ble condition to cause the image thereon to register as to size or position with said reg-
istering guide, and then treating said sheet while maintaining it in such stretched condition to cause the image to retain said reg-
istered condition.

2. The hereindescribed process of preparing flexible printing films or sheets to enable prints to be made in required register from an image on the sheet, which consists in holding the sheet so that the tension thereon can be altered, treating the sheet to render it susceptible to change in size or form, regulating the tension on the sheet as necessary while in such susceptible condition to cause the image thereon to register as to size or position with reference to a registering guide, and then treating said sheet while maintaining it under tension to cause the image to retain said registered condition. 70

3. The hereindescribed process of preparing flexible printing films or sheets to enable photographic prints to be made in required register from an image on the sheet, which consists in holding the sheet so that the tension thereon can be altered, treating the sheet to render it susceptible to change in size or form, regulating the tension on the sheet as necessary while in such susceptible condition to cause the image thereon to register as to size or position with a registering guide, and then treating said sheet while maintaining it under tension to make the sheet transparent and cause the image to retain said registered condition. 80

4. The hereindescribed process of treating a flexible film or sheet bearing an image to cause said image to register with a registering guide, which consists in moistening said sheet to render it extensible, then stretching said sheet as necessary while in such extensible condition to cause the image thereon to register as to size or position with said registering guide, and then drying said sheet while maintaining it in such stretched condition to cause said image to retain said registered condition. 95

5. The hereindescribed process of treating a flexible film or sheet bearing an image to cause said image to register with a registering guide, which consists in moistening said sheet to render it extensible, then stretching said sheet as necessary while in such extensible condition to cause the image thereon to register approximately as to size or position with said registering guide, drying said sheet while maintaining it in such stretched condition, treating said dried sheet again to render it extensible, again stretching it to cause said image to register exactly with said registering guide, and then drying said sheet 110 while maintaining it in said stretched condition to cause said image to retain said registered condition. 115

6. The hereindescribed process of treating a flexible film or sheet bearing an image to cause said image to register with a registering guide, which consists in moistening said sheet to render it extensible, then stretching said sheet as necessary while in such extensible condition to cause the image thereon to 120

register approximately as to size or position with said registering guide, drying said sheet while maintaining it in such stretched condition, then treating said sheet to render it 5 impervious to moisture, then manipulating the sheet to insure exact register of the image with said registering guide, and then treating the sheet while maintaining it taut to cause the image to retain said registered 10 condition.

7. The herein-described process of treating a flexible film or sheet bearing an image to cause said image to register with a registering guide, which comprises holding the sheet so 15 that the tension thereon can be altered, subjecting the sheet to moistening and drying treatment and regulating the tension on the sheet as necessary during the treatment thereof to cause the image on the sheet to register as to size or position with said registering guide, and treating the sheet while maintaining it under tension to cause the image to retain said registered condition.

8. The herein-described process of preparing 25 a flexible film or sheet and making prints in required register from an image on the sheet, comprising holding the sheet so that the tension thereon can be altered, treating the sheet to render it susceptible to change in 30 size or form, regulating the tension on the sheet as necessary while in such susceptible condition to cause an image thereon to register as to size or position with reference to a registering guide, treating said sheet while 35 maintaining it under tension to cause the image to retain said registered condition, and then making prints from said sheet while it is still maintained under tension in said registered condition.

40 9. The herein-described process of preparing a sheet of flexible material bearing an image thereon from which a print is to be made, which includes: conditioning the sheet to render it susceptible to localized changes under 45 variations of tension imposed on the sheet: subjecting the sheet, while in such conditioned state, to varied tensions at different portions thereof, whereby to effect desired changes of the image as to size, position 50 and/or location for obtaining register; and rendering the sheet impervious to moisture.

55 10. The herein-described process of preparing a sheet of flexible material bearing an image thereon from which a print is to be made, which includes: placing the sheet on suitable holding means and attaching thereto around the periphery of the sheet with the sheet substantially taut; subjecting desired portions of the sheet to a treatment of liquid solution 60 characterized by its insolubility in water, whereby to render such portions extensible without rupture; and thereupon subjecting the sheet to desired localized variations of tension and thus inducing changes as to size, position and/or location of the image.

11. The herein-described process of effecting register of an image on a sheet of flexible material, from which a print is to be made, which includes the following steps while the sheet, considered as an entirety, is held in a 70 substantially taut condition: subjecting the sheet to moisture; subjecting the sheet to varied tensions in different areas thereof; drying the sheet; treating the sheet with a solution insoluble in water; and subjecting the 75 sheet to varied tensions.

12. The herein-described process of preparing a sheet of flexible material bearing an image thereon from which a print is to be made, which includes: conditioning the sheet to render it susceptible to changes at any desired 80 portions within the area thereof under variations of tension applied substantially in the plane of the sheet; subjecting the sheet while in such conditioned state to varied tensions 85 at localized points and in localized directions to thereby effect a change of the image as to size, position and/or location relative to other parts of the sheet and thus conform said image to a desired predetermined register; 90 and thereafter treating said sheet to maintain said registered disposition of the image.
